CLAIM

The ornamental design for a pipe flashing, as shown and described.

DESCRIPTION

FIG. 1 is a top plan view of a pipe flashing showing my new design;

FIG. 2 is a bottom plan view thereof;

FIG. 3 is a side elevational view thereof;

FIG. 4 is a fragmentary sectional view taken along line IV—IV of FIG. 1; and

FIG. 5 is a perspective view thereof.

FIG 4

FIG 5
